UNITED STATES PATENT OFFICE

RALPH R. MASON, OF PITTSBURGH, PENNSYLVANIA

PLOT MARKER

Application filed March 11, 1931. Serial No. 521,678.

This invention relates to a plot and lot marker. The object of the invention is to provide a marker which may be used to permanently and accurately mark the corners of lots, cemetery plots, etc.; and, further, to provide a marker which offers relatively great resistance to its removal from the ground when it has been placed, and which is so arranged that it may provide the desired characteristics of accurate marking and difficult removal when cast integrally as a single metallic piece or member.

In the accompanying drawing, Fig. I is an elevation of my marker; Fig. II is likewise an elevation, but taken at right angles to Fig. I; Fig. III is an elevation of a modified form of marker; Fig. IV is an isometric fragmentary view of the lower portion of the marker shown in Figures I and II; and Fig. V is a plan view of the marker shown in Figures I, II and IV.

My marker is cast of a suitable metal such as a non-corrosive bronze, and comprises primarily a shank 1, a terminal vane 2 on the shank, and a head 3 disposed at the end of the shank opposite the vane, and arranged to extend at right angles to the longitudinal axis of the shank. Shank 1 comprises two intersecting legs or webs 1a or 1b, and terminates in the vane 2 which is of rectangular contour in elevation, and which has portions 2a of relatively great area formed as continuations of the web 1a of the shank.

The head 3 of the marker is a plate shown as circular which lies upon the surface of the ground or other material into which the marker is driven. As shown, the marker head is provided with one or more relatively deep score lines 3a to indicate the exact line of division between plots. The head may be provided with a punch mark or other index, to serve as a bench mark for land recording, surveying, and the like. Immediately beneath the head the shank webs 1a are extended to provide additional supporting webs 4 for the marker head.

In the use of the marker, it is desirably first supported by a suitable anvil or the like, and appropriate markings made on the

upper surface of head 3, by means of an indenting die or dies. During this marking, probability of breaking the relatively flat head 3 is minimized by the supporting webs 4 which underlie the head.

In driving the marker, terminal vane 2 at the lower end of shank 1 serves as a blade to enter the ground and facilitate driving the marker as a whole. When the marker has been driven in position its form prevents it from being worked loose in the ground. The lateral movement necessary for working the marker loose is resisted by the intersecting webs 1a and 1b of the shank, and is also resisted by the terminal vane 2. It is difficult to loosen terminal vane 2 in the ground, as any slight angular movement is resisted because of the relatively wide spread of its extending portions 2a. As but little leverage can be obtained by working the head 3, it is necessary that the marker be dug from the ground when it has once been driven in to its full length.

The marker as a whole forms a simple integral casting since the extensions 2a of the vane 2 and the supporting webs 4 for the head 3 are formed as extensions of the shank web 1a. The proportions of the marker are such as to obtain a maximum of security when the marker is driven, without unduly increasing the size of the marker and the quantity of metal comprised in it.

The modified form of marker shown in Fig. III of the drawing is identical with the form shown in the other figures, with the exception that the shank webs 1a and 1b are serrated in such manner that shoulders 5 are formed in staggered position around the shank of the marker. Obviously the shoulders 5 do not resist driving of the marker, but do serve to increase the difficulty of withdrawing the marker by means of a straight pull. In this form of marker also the terminal vane 2 and the intersecting webs 1a and 1b prevent loosening of the marker in the ground by attempts to move it laterally to provide clearance.

I claim as my invention:

1. A plot marker formed as a single metallic driving piece comprising a shank

formed of intersecting ground engaging webs, a flattened marker head on said shank disposed at right angles to the longitudinal axis of the shank, one of said intersecting webs extended terminally to form a plane ground penetrating and engaging member with a penetrating edge lying at right angles to the longitudinal axis of the shank and extending in opposed directions outwardly from the shank, said member being of substantial depth throughout its lateral extent to present terminally disposed surfaces of relatively great area resisting turning movement of the marker when driven.

15 2. A plot marker formed as a single metallic driving piece comprising a shank formed of intersecting ground engaging webs, a flattened marker head on said shank disposed at right angles to the longitudinal axis of the shank, one of said intersecting webs extended terminally to form a plane ground penetrating and engaging member with a penetrating edge lying at right angles to the longitudinal axis of the shank and extending in opposed directions outwardly from the shank, said member being of substantial depth throughout its lateral extent to present terminally disposed surfaces of relatively great area resisting turning movement of the marker when driven, and strengthening webs beneath the head of the marker formed as lateral extensions of at least one web of the shank.

In testimony whereof I have hereunto set
35 my hand.

RALPH R. MASON.
